UNITED STATES PATENT OFFICE.

OTTO WIEDEKE, OF DAYTON, OHIO.

TUBE-CUTTER.

1,162,893.

Specification of Letters Patent.

Patented Dec. 7, 1915.

Application filed September 11, 1915. Serial No. 50,188.

To all whom it may concern:

Be it known that I, OTTO WIEDEKE, a citizen of the United States, residing at Dayton, in the county of Montgomery and State of Ohio, have invented certain new and useful Improvements in Tube-Cutters; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in tube cutters and particularly to the driving and controlling means thereof.

The object of the invention is to provide a driving and controlling means through the aid of which a manually operated tube cutter may be driven from a motor or other source of power.

To the above end the device is simple in construction and efficient in operation.

Referring to the accompanying drawings, Figure 1 is a longitudinal section through a tube cutter with my invention attached thereto; Fig. 2 is a side elevation of the same; Fig. 3 is a section approximately on the line 3—3 of Fig. 2; Fig. 4 is a view similar to Fig. 3 with the parts in a different position; Fig. 5 is a section on the line 5—5 of Fig. 1; Fig. 6 is a section on the line 6—6 of Fig. 3; Fig. 7 is a plan view of one of the releasable nut sections; and Fig. 8 is a plan view of the supporting shaft of the attachment.

In the specification and drawings, similar reference characters indicate corresponding parts.

Referring more particularly to the drawings, 1 represents a tube sheet of a boiler which receives a boiler tube 2. The tube 2 extends past the tube sheet 1 to a greater extent than is necessary to bead the end of the tube in the sheet. This extended portion of the tube is cut off by the following means: Adapted to be inserted within the tube is a hollow frame 3 which receives a carrier 4 provided with a roller cutter 5. The frame 3 also is provided with a carrier 6 which receives rollers 7. The carriers 4 and 6 are adapted to be pressed outwardly by a wedge-shaped actuator 8 mounted within the frame

3. When the actuator 8 is moved longitudinally and the frame 3 is rotated, the cutter 5 is pressed into the inner side of the tube 2 thereby cutting off the end of the tube and beveling the same preparatory to beading the end of the tube in the tube sheet 1. The position of the cutter 5 relative to the tube sheet is regulated by an adjustable guard 9 which is adapted to slide on the frame 3. The actuator 8 is attached to a rod 10 by means of which it is moved.

The above described device forms one well known type of tube cutter which, as far as my attachment is concerned, may be of any of the well known types.

The above tube cutter is machine-driven through the aid of my attachment as follows: A hollow shaft 12, provided with a squared end 13 to which a motor or other suitable driving means may be attached, is adapted to be attached to the frame 3 by means of a screw 11 and lugs 11'. When the shaft 12 is rotated, the frame 3 is also rotated and, during the time of the rotation of the shaft 12 and frame 3, the cutter 5 is moved outwardly automatically by the following means: Attached to the end of the rod 10 is an extension 14 provided with a race 15 which receives the ends of screws or pins 16. Said screws or pins 16 extend through slots 35 and are mounted in a collar 17 slidingly mounted on the shaft 12. The collar 17 is moved along the shaft 12 to move the cutter 5 outwardly by the following means: The said collar 17 is provided with an anti-friction bearing 18 which is in engagement with a spacing collar 19 mounted on the shaft 12. The said spacing collar 19 is in direct engagement with two split nut portions 20 also mounted on the shaft 12. These split nut portions are provided with ears 21 provided with pins 22 which permit the nut portions to open and close. The said nut portions 20 are opened by pins 23 which ride or press against the shaft 12. The pins 23 are mounted in pockets 24 and are under the control of springs 25. The nut portions 20 are provided with screw-threads 26 adapted to be placed in and out of engagement with screw-threads 27 on the shaft 12. The screw-threads 26 are disengaged from the screw-threads 27 by the springs 25 and pins 23, but are placed in engagement by the following means: One of the nut portions 20 is provided with a cam 28, while the other por-

tion is provided with a boss 29. The said boss receives a pivot pin 30 on the end of a hand lever 31 which is provided with an adjustable pin 32 adapted to engage a cam 28. 5 When the pin 32 is in the position shown in the drawings, the said pin and cam 28 have placed the threads 26 in engagement with the threads 27. It will be seen that when the parts are in this position, the shaft 12 is rotated and the nut portions 20 are held stationary by holding the lever 31 in the hand, the nut portions 20 will slide along the shaft 12 thereby shifting the collar 17, the extension 14, the rod 10, the actuator 8, and moving the cutter 5 outwardly to sever the tube. 10 When the tube 2 has been completely severed, the actuating means for the cutter may be released by shifting the lever 31 which allows the springs 25 to disengage the threads 26 from the threads 27. When this operation takes place, the nut portions 20 are moved to a normal position and the cutter 5 is released by a spring 33 which may be mounted within the shaft 12 but which, in the present 15 instance, lies between the collar 17 and a collar 34 mounted on the shaft 12. During the return of the nut portions 20 to a normal position, the threads 26 are held out of engagement with the threads 27, by the pins 20 23 and springs 24.

The shaft 12, in the present instance, is shown and described as an extension of the frame 3 but it will be understood that the tool in its entirety may be constructed with 35 the shaft 12 as an integral portion of the frame 3. Also, the shaft 12 may be attached to the frame 3 by the aid of an "extension", not shown, to permit the tool to be used in connection with the heads of water tube 40 boilers.

In operating the tool, the operator will insert the frame 3 within the end of the tube until the guard 9 comes in contact with the tube sheet 1. The nut portions 20 are then 45 contracted by shifting the hand lever 31 which places the threads 26 in engagement with the threads 27. The nut portions 20 are then held stationary by holding the lever 31 in the hand and the tool is then rotated 50 by starting the motor or other driving means. When the shaft 12 rotates relative to the nut portions 20, said nut portions will slide along the shaft 12 against the tension of the spring 33 thereby moving the cutter 5 outwardly. 55 When the cutting operation has been completed, the cutter 5 is released and the parts are returned to a normal position by a spring 33, by shifting the lever 31 which disengages the pin 32 from the cam 28.

60 Having described my invention, I claim—

1. In a device of the type specified, a rotating member, cutting means mounted in said rotating member having screw threads, split nut members operatively connected to 65 said cutting means, means for placing said

nut members in engagement with said screw-threads, including a cam on one of said nut members and a lever, and a means adapted to return said nut members to a normal position and to release said cutting means. 70

2. In a device of the type specified, rotating means, cutting means mounted in said rotating means having screw threads, split nut members adapted to be placed in engagement with said screw-threads, means 75 for disengaging said nut members from said screw-threads, a cam on one of said nut members, and a lever in operative relation with said cam and adapted to place said nut members in engagement with said screw-threads. said nut members being operatively connected to said cutting means. 80

3. In a tube cutter, rotating means having screw threads, cutting means mounted in said rotating means, a sectional nut adapted 35 to be placed in engagement with said screw-threads, means for disengaging said nut sections from said screw-threads, a cam on one of said nut sections, a lever in operative relation with said cam and adapted to place 90 said nut sections in engagement with said screw-threads, said nut sections being operatively connected to said cutting means, and a spring adapted to return said nut sections to a normal position and to release 95 said cutting means.

4. In a tube cutter, rotating means having screw threads, cutting means mounted in said rotating means, a divided nut adapted 100 to be placed in engagement with said screw-threads, one portion of said nut being provided with a cam, spring-pressed pins mounted in said divided nut and adapted to disengage said divided nut from said screw-threads, a lever in operative relation with 105 said cam on one of the nut portions and pivoted to the other of said nut portions and adapted to place said nut portions in engagement with said screw-threads, connections between said nut portions and said cutting means, and a spring adapted to return 110 said nut portions to a normal position and to release said cutting means.

5. In a tube cutter, a rotating member having screw threads, a cutting member mounted in said rotating member, a two-part nut mounted on said rotating member and adapted to be placed in engagement with said screw-threads, spring-pressed pins mounted in said two-part nut and adapted 115 to disengage said nut portions from said screw-threads, a cam mounted on one of said nut portions, a lever pivoted to the other of said nut portions, said lever being in operative relation with said cam and adapted to place 120 said nut portions in engagement with said screw-threads, a collar slidably mounted on said rotating means and adapted to be actuated by said two-part nut and operatively connected with said cutting means, 125 130

and a spring adapted to actuate said collar to return said nut portions to a normal position and to release said cutting means.

6. In a tube cutter, a rotating member having screw threads, a cutting member mounted in said rotating member, a two-part nut adapted to be placed in engagement with said screw-threads and one of which is provided with a cam, spring-pressed pins mounted in said nut portions and adapted to disengage said nut portions from said screw-threads, a lever pivoted to one of said nut portions, an adjustable pin carried by said lever in operative relation with said 10 cam and adapted to place said nut portions in engagement with said screw-threads, a shiftable collar provided with an anti-friction bearing and adapted to be actuated by said two-part nut, pins mounted in said 15 shiftable collar, a rod provided with a race which receives said pins and connected to said cutting member, and a spring being adapted to actuate said shiftable collar to move said nut portions to a normal position 20 and to release said cutting member.

7. In a tube cutter, a rotating frame, cutting means mounted in said frame, a shaft attached to said frame, said shaft being hollow and provided with longitudinal slots 30 and screw-threads, a two-part nut adapted to be placed in engagement with said threads and one part of which has a cam, spring-pressed pins mounted in said two-part nut and adapted to disengage said nut from said threads, a lever pivoted to the other part of said nut portions in operative relation with said cam and adapted to place said nut in engagement with said threads, a shiftable 35

collar mounted on said shaft, pins mounted in said collar and extending through said 40 slots, a rod provided with a race which receives said pins, a spacing collar mounted between said shiftable collar and the nut portions, and a spring adapted to actuate said shiftable collar to return said nut portions to a normal position and to release 45 said cutting means.

8. In a tube cutter, a rotatable frame, cutting means mounted in said rotating frame, a shaft forming an extension of said frame 50 having screw-threads, a split nut one portion of which has a cam, said nut being adapted to be placed in engagement with said screw-threads, spring-pressed pins mounted in said nut and adapted to disengage 55 said nut portions from said screw-threads, a lever pivoted to one of said nut portions, an adjustable pin mounted on said lever in operative relation with the cam on the nut portion and adapted to place said 60 nut portions in engagement with said screw-threads, said shaft being hollow and provided with longitudinal slots, a shiftable collar having anti-friction bearings mounted on said shaft, pins mounted in said collar 65 and extending through said slots, a rod provided with a race which receives said pins, a spacing collar mounted on said shaft between said anti-friction bearings and said 70 nut portions, and a spring adapted to actuate said shiftable collar to return said nut portions to a normal position and to release said cutting means.

In testimony whereof I affix my signature.

OTTO WIEDEKE.
